ANTISEPTIC ACRIDANE COMPOUNDS

Donalee L. Tabern, Lake Bluff, Ill., assignor to
Abbott Laboratories, North Chicago, Ill., a corporation of Illinois

No Drawing. Application October 19, 1948,
Serial No. 55,424

28 Claims. (Cl. 167—65)

2

This invention relates in general to acridine compounds and more specifically to substituted acridine compounds of the following structure, which are more properly called acridanes:

wherein R is an alkyl group containing from one to fourteen carbon atoms inclusive; X is a monovalent radical selected from class comprising hydrogen, halogen, alkyl and alkoxy groups; Y is a hydrocarbon group containing from one to ten carbon atoms inclusive and Z is a mineral acid anion. Other useful compounds of the present invention have also been prepared in which Z is an alkoxy group (the alkyl group of which contains from one to four carbon atoms inclusive), or a hydroxyl group.

The —OR group in the above formula may be in any position: ortho, meta or para. For ease in preparation the para compound is often preferred.

It has long been known that various of the acridines have served as antiseptics and germicides. Among the most important of these are proflavine and acriflavine.

The acridines are characterized by a heterocyclic central ring containing one nitrogen atom as indicated in the structural formula below:

In the compounds of this invention, the antiseptic properties are greatly enhanced over those of the acridines.

I have discovered that by introducing a hydrocarbon substituent on the ring (10) nitrogen of the acridine and an alkoxy-phenyl group on

the 9-carbon, compounds are obtained, which, when converted to suitable salts, such as the halide or sulfate, have unique physiological properties. These compounds are usually light yellow to orange in color. They are soluble in water or in the usual tincture menstrua at pH ranges of 3 to 7. These solutions are stable to light and air; remaining unchanged for many months. In the concentrations required for sterilization of the skin or mucous surfaces, they cause little irritation. These compounds penetrate the skin and due to their color stain it, but such stains may readily be removed by washing the skin with soap and water.

Instead of the above salt forming groups (a mineral acid anion such as a halide or sulfate), Z may be an alkoxy group containing up to four carbon atoms inclusive, preferably methoxyl. In this case the compounds are colorless and insoluble in water; but are valuable in that they facilitate the isolation and purification of the reaction products.

The water-soluble acridane salts are active against a wide variety of organisms both gram positive and gram negative and even against certain pathogenic fungi. Their antiseptic activity persists to a great extent even in the presence of such organic matter as gelatine, sputum and sera. As little as 1 milligram of the compounds of this invention per 100 cc. of saliva acts as an antacid in the mouth which is so important in the prevention of tooth decay. Moreover, most of these compounds are only moderately bitter, and in view of the above stated properties are valuable in treating infections of the throat and mouth.

An increase in the size of the alkyl group of the alkoxy-phenyl substituent from methoxy to n-hexoxy increases the antiseptic power many fold even when in dilutions of 1 to 5,000,000 for the latter compounds. Investigations also indicate that as the size of this chain is increased, the surface tension of the aqueous solutions decreases, giving increased drug penetration. The alkoxy group may be on any position of the phenyl ring: ortho, meta or para. From the standpoint of ease of preparation, the p-alkoxy phenyl compounds are preferred.

The hydrocarbon group Y may be an alkyl, aryl or aralkyl group containing one to ten carbon atoms inclusive. For ease of manufacture

and economy, the groups are preferably methyl, ethyl, phenyl, or benzyl. The compounds of the invention may be further substituted in the acridine rings. Also one of these rings may be saturated or heterocyclic.

The processes of synthesizing the substituted anthranilic acids and simple acridones used as intermediates are in general those of the literature. Acridones are characterized by the following structure:

For example, acridone may be prepared from phenylanthranilic acid by ring closure with sulfuric acid or with phosphorous pentachloride plus aluminum chloride.

For the preparation of substituted N-alkyl, or aralkyl acridones the processes of the prior art have been found less satisfactory than those that I have discovered. These latter processes are described below:

An acridone is treated with a dialkyl sulfate as illustrated above to give the N-alkylated acridone. More specifically, this process can be carried out to give N-methyl acridone by reacting acridone with dimethyl sulfate as illustrated by the example below:

EXAMPLE IA

About 10 gms. of acridone and 15 gms. of sodium hydroxide are dissolved in alcohol with stirring and heating. Most of the solvent is then distilled off and replaced by a hydrocarbon solvent such as xylene and preferably a solvent boiling between 100° and 150° C. To this solution is added 10 to 15 gms. of dimethyl sulfate dissolved in dry acetone and the mixture warmed. On cooling the resulting methyl acridone precipitates. The precipitate is then filtered and purified by crystallization. The yield from this process is from 85-90% of the theoretical.

An alternative process for the preparation of N-alkyl acridones reacts an alkali-metal alcoholate with the acridone to form the alkali-metal salt of the acridone. This product is reacted with an alkyl halide to form the N-alkyl acridone. This reaction may be illustrated by the following illustration:

wherein M is an alkali metal, R is an alkyl group, R' is an alkyl or aralkyl group and X may be chlorine, bromine or iodine. A specific example to illustrate this process is given below.

EXAMPLE IB

About 15 gms. of potassium metal is dissolved in an excess of methyl alcohol. To this solution is added about 50 gms. of acridone and the excess alcohol is removed by distilling with xylene. Hexyl chloride in the amount of 125 gms. is added to the mixture and the whole heated in a rocking bomb at 130°-140° C. for four hours. The product N-hexyl acridone is isolated as in Example IA and purified by recrystallization from alcohol.

EXAMPLE IC

In a manner similar to that of Example IB, N-benzyl acridone may be prepared by reacting 30 gms. of the potassium salt of acridone with 2 moles of benzyl chloride at 130-140° C. for nine hours to give 9 gms. of product melting at 180-181° C.

N-aryl acridones are best prepared from the appropriate triphenylamine carboxylic acids by ring closure.

By the use of the above procedures the N-substituted acridones used as intermediates may be prepared.

Neither do the processes reported in the literature for the preparation of compounds similar to the acridanes of the invention work well. These processes teach using the Grignard reagent and the result of the process is the formation of an insoluble Grignard complex which will not react further. I have discovered a new process for making 9-alkoxy-phenyl-10-hydrocarbon substituted acridine derivatives which may be outlined as follows: A halo (such as iodo)-aryl-alkoxy compound (I) is reacted with an alkali metal such as lithium in an inert solvent such as ether to form the lithium derivative (II). The lithium derivative reacts rapidly with the N-substituted acridone (III) (see Examples IA, IB, IC) to give the essentially pure acridol (IV) in practically quantitative yields. The reaction product remains dissolved in the solvent. Addition of gaseous hydrogen halides gives the ether insoluble halide (V) or halo-hydrochloride (VI) which are lemon yellow powders which may be removed by filtration. When the halo-hydrohalide is dissolved in an inert solvent such as chloroform and a neutralizing agent such as dry calcium carbonate is added, which removes the excess acid, a neutral halide acridane (VII) is obtained which is very soluble in water and alcohol. This latter product may also be obtained by drying the halo-hydrohalide with heat.

Some of the mineral-acid anion acridones are difficult to purify. Therefore, for purification or characterization it may be convenient to isolate the crude acridols (IV and VIII) by addition of excess alkali to the solution of the halide (V) in water. These acridols upon warming with an alkanol such as methanol give colorless and usually crystalline methoxyl derivatives (IX). The addition of an excess of hydrogen halide will reconvert the methyl ether to the halide (V). Sulfuric acid may be used in this synthesis in place of the hydrogen halide to form the bisulfate. This process may be illustrated by the following

reactions with the compounds numbered to conform to the description above:

wherein R is an alkyl group containing from one to fourteen carbon atoms inclusive; X is a monovalent radical selected from the class comprising hydrogen, halogen, alkyl and alkoxy groups; Y is a hydrocarbon group containing one to ten carbon atoms inclusive; Z is a mineral acid anion such as chlorine, bromine, iodine and sulfate.

In the formulae above it is understood that the aromatic rings may be suitably substituted.

It is possible to write several tautomeric formulae for the products which are the subject of this invention. The ethers are, as has been stated, colorless and possess the structure:

By analogy the halide and sulfate derivatives would possess the structure:

These derivatives, on the other hand, are deeply colored. It was shown many years ago [Journal American Chemical Society 48, 1345 (1926)] that in the case of certain related compounds, these derivatives may form by a simultaneous tautomerization to a "quinonoid" form, expressible in this case as

On the other hand, by convention, "proflavine" is written as containing a pentavalent nitrogen

and by analogy these compounds could be represented by

Quite obviously, the exact mode of expressing the structure here under discussion is immaterial and for purposes of generalization the formulation

is used always keeping in mind that the product at hand may be predominantly one form or the other, or a tautomeric mixture of these forms.

Many of these compounds possess quite unexpected physical properties. For instance, the

7 chloride hydrochloride (VI) is soluble in hot toluene, and may be extracted from water by chloroform.

Specific examples illustrative of the general process described above are given below.

EXAMPLE II

9-(*p*-*n*-hexoxyphenyl)-10-methyl acridane chloride

To approximately 1.4 gms. of lithium suspended in 100 cc. of anhydrous ether is added drop-wise about 30 gms. of *p*-(*n*-hexoxy)-phenyl iodide at such a rate that the surface of the metal remains bright. When the reaction ceases, as evidenced by the solution of the lithium metal, an amount of from 19 to 21 gms. of powdered, dry N-methyl acridone is added gradually. This reaction mixture is refluxed for 2 or 3 hours following which ice water is added along with sufficient diethyl ether to dissolve the organic matter present. The ether solution is separated, washed with water, dried and treated with gaseous hydrogen chloride. The insoluble chloride hydrochloride is thus formed which is separated by filtration and recrystallized from toluene. The chloride hydrochloride may be converted to the chloride either by drying the compound with heat or by dissolving the chloride hydrochloride in chloroform and treating this solution with dried calcium carbonate. If the latter procedure is used the excess calcium carbonate and calcium chloride formed may be removed by filtration. The chloride is obtained by evaporating the chloroform solvent and recrystallizing from toluene. The compound melts at 184.5-185.5° C. with decomposition. The compound is readily soluble in water, alcohol and other polar solvents. Physically this compound is in the form of fine, dark yellow crystals. Its solutions are light yellow in color and are stable to light and air. It stains the skin to a clear yellow color which color is readily removed by washing with soap and water.

EXAMPLE III

9-(*p*-*n*-hexoxyphenyl)-10-methyl acridane bisulfate

To approximately 1.5 grams of lithium metal

8 in 200 cc. of anhydrous ether which has been heated to reflux is added 25.7 grams of *p*-bromo-phenyl-*n*-hexyl ether, with stirring over a period of about one hour. After further stirring and refluxing, the mixture is cooled somewhat and 20.9 grams of N-methyl acridone is added over a period of about 10 minutes. After a short period of further stirring and refluxing, the solution is cooled, filtered and poured into 250 cc. of ice and water. The ether solution and the water solution separate into two phases. The aqueous phase is extracted with 75 cc. of ether. This ether extract is combined with the ether phase, washed twice with water and dried over anhydrous magnesium sulfate. The light orange colored solution is filtered, treated with adsorbing charcoal and refiltered. The filtrate is orange-yellow in color. The ethereal solution contains 9-(*p*-*n*-hexoxyphenyl)-10-methyl-9-acridol.

One half of the above solution containing the carbinol is diluted into 150 cc. with anhydrous ether. To this solution is added dropwise a solution of 5.16 grams of 95% sulfuric acid dissolved in 50 cc. of ether until the precipitation of the orange-yellow bisulfate is complete. This requires about one half of the ethereal sulfuric acid solution. This precipitate is removed by filtration, washed twice with ether and twice with *n*-hexane and dried in vacuum at 50° C.

The crude bisulfate form is purified as follows:

About 7.0 grams of crude sulfate obtained above is dissolved in about 100 cc. of toluene and about 10 cc. of absolute ethanol, at the boiling point of the solvent. The solution is concentrated by distilling off most of the alcohol. Toluene is added and most of the remainder of the ethanol distilled off. On seeding with the crude bisulfate, the pure product begins to crystallize from the solution. After the solution has been cooled the bisulfate is filtered, washed with toluene and dried at 50° C. in vacuum. The yellowish-orange platelets of 9-(*p*-*n*-hexoxyphenyl)-10-methyl acridane bisulfate melt at 229-230.5° C. with decomposition. The product analyzes for the bisulfate rather than the sulfate.

EXAMPLE IV

9-(*p*-*n*-hexoxyphenyl)-10-methyl acridane bromide

To one half of the ether solution of the 9-(*p*-hexoxyphenyl)-10-methyl-9-acridol prepared according to Example III, is added enough anhydrous ether to dilute the solution to 150 cc. To this solution is added dropwise a solution of 4.5 grams of hydrogen bromide gas dissolved in 50 cc. of anhydrous ether until precipitation of the yellowish-orange product is complete. Approximately one half of the above ethereal hydrogen bromide is needed. The crude bromide

form is filtered, washed three times with n-hexane and dried in vacuum at 50° C.

About 7.0 grams of the crude bromide is dissolved in 100 cc. of boiling toluene. The solution is concentrated until the product begins to crystallize from the boiling solution. The solution is cooled, the solid removed by filtration, washed with toluene and dried at 50° C. in vacuum. This procedure is repeated and a further purification accomplished by a third recrystallization from toluene which contains slightly over 1% absolute ethanol. The crystals are filtered, washed with toluene and dried at 50° C. in vacuum. The yellow plates of 9-(p-n-hexoxyphenyl)-10-methyl acridane bromide melts at 178-178.5° C. with decomposition.

EXAMPLE V

9-(p-methoxyphenyl)-10-phenyl acridane chloride

In the same manner as in Example III, p-bromoanisole and lithium are reacted to give p-lithium anisole. The p-lithium anisole is reacted with N-methyl acridone to produce the lithium-salt of 9-(p-methoxyphenyl)-10-phenyl-9-acridol.

This compound may be converted directly into the compound 9-(p-methoxyphenyl)-10-phenyl acridane chloride by filtering the dried ethereal solution of the lithium salt of the acridol and precipitating with ethereal hydrogen chloride. The crude product is filtered, washed with n-hexane and dried at 50° C. in vacuum. The crude product is purified by dissolving in ethyl acetate containing a small amount of absolute ethanol, treating with adsorbing charcoal, filtered, concentrated and cooled. The orange crystals formed are filtered, washed with ethyl acetate and dried at 50° C. in vacuum. The orange, finely crystalline 9-(p-methoxyphenyl)-10-phenyl acridane chloride melts at 172.5-174.5° C.

EXAMPLE VI

9-(o-methoxyphenyl)-10-methyl acridane chloride

In a manner analogous to that of Example V but using o-bromo anisole to prepare the o-lithium anisole and reacting this with N-methyl acridone the crude compound 9-(o-methoxyphenyl)-10-methyl acridane chloride may be prepared. The crude product may be purified as in Example IV by recrystallizing from toluene containing a small amount of absolute ethanol. After repeating the crystallization several times in toluene containing the small amount of absolute ethanol, the product is recrystallized from ethyl acetate containing a trace of ethanol. The compound 9-(o-methoxyphenyl)-10-methyl acridane chloride is in the form of small, dense yellow crystals having a melting point of 208.5 to 209° C. with decomposition.

EXAMPLE VII

9-(p-n-butoxyphenyl)-10-methyl acridane chloride

20

25

30

35

In a manner analogous to that of Example IV reacting lithium metal with p-bromophenyl-n-butyl ether to form the p-lithium compound and reacting this compound with N-methyl acridone, the above mentioned compound may be prepared. After recrystallizing from toluene containing a small amount of absolute ethanol, the compound 9-(p-n-butoxyphenyl)-10-methyl acridane chloride is obtained in the form of small brownish-yellow plates which have a melting point of 186.5-187° C.

EXAMPLE VIII

9-(p-hexoxyphenyl)-10-ethyl acridane chloride

50

55

60

65

In a manner analogous to that of Example II but using n-ethyl acridone with p-lithium phenyl-n-hexyl ether, the above mentioned compound may be prepared. After recrystallization from toluene containing a small amount of absolute ethanol, the compound 9-(p-hexoxyphenyl)-10-ethyl acridane chloride thus prepared is in a form of a light yellow powder having a melting point of 197.5-199° C. with decomposition.

11

EXAMPLE IX

9-(*p*-*n*-hexoxyphenyl)-10-benzyl acridane chlorideIn a manner analogous to Example II but using N-benzyl acridone with *p*-lithium phenyl-*n*-hexyl ether, the above mentioned compound may be prepared. After recrystallization from toluene containing absolute ethanol the compound 9-(*p*-*n*-hexoxyphenyl)-10-benzyl acridane chloride is obtained in the form of orange-yellow crystals having a melting point of 91-98° C. The compound is hygroscopic and difficult to obtain in pure form.

EXAMPLE X

9-(octoxyphenyl)-10-methyl acridane chloride

In a manner analogous to Example II but using *p*-lithium phenyl-*n*-octyl ether and N-methyl acridone, the above mentioned compound may be prepared. After crystallization from toluene, the compound 9-(*p*-*n*-octoxyphenyl)-10-methyl acridane chloride is a golden yellow colored solid having a melting point of 153-155° C. with decomposition.

EXAMPLE XI

9-(*p*-2-ethylbutoxyphenyl)-10-methyl acridane chlorideIn a manner analogous to that of Example II but using *p*-lithium phenyl-2-ethylbutyl ether with N-methyl acridone, the above mentioned compound may be prepared. After crystallization from toluene, the compound 9-(*p*-2-ethylbutoxyphenyl)-10-methyl acridane chloride is ob-

12

tained in the form of yellow needles with a melting point of 157-158° C. with decomposition.

EXAMPLE XII

5 9-(*p*-*n*-decyloxyphenyl)-10-methyl acridane chlorideIn a manner analogous to that of Example II but using *p*-lithium phenyl-*n*-decyl ether and N-methyl acridone the above mentioned compound may be prepared. After crystallization from toluene the compound 9-(*p*-*n*-decyloxyphenyl)-10-methyl acridane chloride is obtained in the form of golden yellow needles having a melting point of 161-164° C. with decomposition.

EXAMPLE XIII

30 2-methoxy-9-(*p*-*n*-hexoxyphenyl)-10-methyl acridane chlorideIn a manner analogous to that of Example II but using *p*-lithium phenyl-*n*-hexyl ether and 2-methoxy-10-methyl acridone, the above mentioned compound may be prepared. After crystallization from toluene containing a small amount of absolute ethanol the compound 2-methoxy-9-(*p*-*n*-hexoxyphenyl)-10-methyl acridane chloride is obtained in the form of bright orange crystals having a melting point of 196.5-197° C. with decomposition.

EXAMPLE XIV

55 1-chloro-9-(*p*-*n*-hexoxyphenyl)-4,10-dimethyl acridane chlorideIn a manner analogous to that of Example II but using *p*-lithium phenyl-*n*-hexyl ether with 1-chloro-4,10-dimethyl acridone, the above men-

tioned compound may be prepared. After crystallization from ethyl acetate containing a small amount of absolute ethanol a compound 1-chloro - 9 - (p - n-hexoxyphenyl)-4,10-dimethyl acridane chloride is obtained as brilliant orange-red platelets having a melting point of 98-102° C. with decomposition.

EXAMPLE XV

9-(p-n-tetradecyloxyphenyl)-10-methyl acridane chloride

In a manner analogous to that of Example II the above mentioned compound may be prepared by reacting p-lithium phenyl-n-tetradecyl ether and N-methyl acridone. The compound may be purified in the previous examples.

EXAMPLE XVI

9-(p-n-methoxyphenyl)-10-n-decyl acridane chloride

In accordance with the process of Example II the above mentioned compound may be prepared by reacting p-lithium phenyl-methyl ether with N-n-decyl acridone. The compound may be purified in the same manner as in the previous examples.

The alkyl groups of the 9-alkoxyphenyl substituent may be in cyclic form. For example, by starting with a p-cyclohexyloxyphenyl halide and reacting the lithium salt with N-methyl acridone, the compound produced is 9-(p-cyclohexyloxyphenyl)-10-methyl acridane chloride. In addition to having the alkoxy group in the para and ortho positions the group may be in the meta position. For example, by starting with the lithium phenyl-m-methyl ether and reacting this with N-methyl acridone, the compound produced is 9-(m-methoxyphenyl)-10-methyl acridane chloride.

The above compounds are unique in that their solutions have a low surface tension and other favorable properties with in agar disc plates give wide zones of bacterial inhibition.

At times it is difficult to purify the above mentioned acridane-mineral acid salts of the invention. Frequently repeated recrystallization results in no improvement of purity since it only accomplishes further decomposition. It has been found to be exceedingly advantageous to produce the corresponding 9-alkoxy acridane as an inter-

mediate for purification. These compounds are easily purified and are an excellent source for obtaining pure acridane-mineral acid anion salts. The 9-alkoxy acridane derivative may be prepared as indicated above by adding an excess of alkali to a solution of the acridane-mineral acid anion salt to produce the acridol. By simply warming the acridol formed with an alcohol, the corresponding 9-alkoxy acridane is obtained. Investigation shows that the methoxy derivative obtained by refluxing with methyl alcohol are the most desirable 9-alkoxy acridane compounds. The following examples illustrate the preparation of the 9-acridols and 9-alkoxy acridanes.

15

EXAMPLE XVII

9-(p-hexoxyphenyl)-9-methoxy-10-methyl acridane

20

An aqueous solution of 9-(p-hexoxyphenyl)-10-methyl acridane chloride (see Example II) or the bisulphate (see Example III) or a bromide (see Example IV) is covered with ether and treated with a dilute solution of alkali. The ether layer is separated, washed free of alkali and dried over anhydrous magnesium sulphate and adsorbing charcoal. The solution is filtered and concentrated to a residue. The residue is dissolved in n-hexane, the solution evaporated to a small volume. On cooling, the compound 9-(p-hexoxyphenyl)-10-methyl-9-acridol crystallizes from the solution having a melting point of 85° C.

The above mentioned acridol is refluxed in absolute methanol. On cooling, the compound 9-(p-hexoxyphenyl)-9-methoxy-10-methyl acridane crystallizes out, is filtered, washed with methanol and dried in vacuum at 50° C. This compound has a melting point of 77-78° C.

50

EXAMPLE XVIII

9-(p-methoxyphenyl)-9-methoxy-10-phenyl acridane

65

In accordance with the procedure of Example XVII and starting with the compound 9-(p-methoxyphenyl)-10-phenyl acridane chloride (see Example V), the compound 9-(p-methoxyphenyl)-10-phenyl-9-acridol is obtained upon treatment with alkali. This compound has a melting point of 152-155° C.

75

15

Treatment of the above mentioned acridol with methanol yields the compound 9-(*p*-methoxyphenyl)-9-methoxy-10-phenyl acridane, having a melting point of 158.5-160.5° C.

EXAMPLE XIX

9-(*o*-methoxyphenyl)-9-methoxy-10-methyl acridaneFollowing the procedure of Example XVII but using 9-(*o*-methoxyphenyl)-10-methyl-acridane chloride, (see Example VI), the compound 9-(*o*-methoxyphenyl)-10-methyl-9-acridol is obtained upon alkali treatment. This compound has a melting point of 132-135° C.

The treatment of the above acridol with methanol yields 9-(*o*-methoxyphenyl)-9-methoxy-10-methyl acridane, having a melting point of 162-163° C. with decomposition.

EXAMPLE XX

9-(*p*-n-butoxyphenyl)-9-methoxy-10-methyl acridaneBy following the procedure of Example XVII but starting with the compound 9-(*p*-n-butoxyphenyl)-10-methyl acridane chloride (see Example VII), the compound 9-(*p*-n-butoxyphenyl)-10-methyl-9-acridol is obtained upon alkali treatment. This compound has a melting point of 103-105° C.

The above acridol is converted to the compound 9-(*p*-n-butoxyphenyl)-9-methoxy-10-methyl acridane upon refluxing with methanol. This compound has a melting point of 102-103° C. A mixed melting point determined between this compound and the acridol precursor gives a melting point of 83-88° C. showing that the two compounds are different.

EXAMPLE XXI

9-(*p*-n-hexoxyphenyl)-9-methoxy-10-ethyl acridane2,645,594

16

By following the procedure of Example XVII starting with the compound 9-(*p*-n-hexoxyphenyl)-10-ethyl acridane chloride (see Example VIII), the compound 9-(*p*-n-hexoxyphenyl)-10-ethyl-9-acridol is prepared upon treatment with alkali. The refluxing of this acridol compound with methanol produces the compound 9-(*p*-n-hexoxyphenyl)-9-methoxy-10-ethyl acridane.

EXAMPLE XXII

9-(*p*-n-hexoxyphenyl)-9-methoxy-10-benzyl acridane10

15

20

25

30

35

40

45

50

60

65

70

75

By following the procedure of Example XVII starting with 9-(*p*-n-hexoxyphenyl)-10-benzyl acridane chloride (see Example IX), the compound 9-(*p*-n-hexoxyphenyl)-10-benzyl-9-acridol is prepared upon treatment with alkali. This compound has a melting point of 126.5-128.5° C. Refluxing of this acridol compound with methanol produces the compound 9-(*p*-n-hexoxyphenyl)-9-methoxy-10-benzyl acridane, having a melting point of 118.5-120.5° C.

EXAMPLE XXIII

9-(*p*-n-octyloxyphenyl)-9-methoxy-10-methyl acridane40

45

50

60

65

70

75

By following the procedure of Example XVII but starting with 9-(*p*-n-octyloxyphenyl)-10-methyl acridane chloride (see Example X), the compound 9-(*p*-n-octyloxyphenyl)-10-methyl-9-acridol is obtained on treatment with alkali. This acridol upon refluxing with methanol is converted to the compound 9-(*p*-n-octyloxyphenyl)-9-methoxy-10-methyl acridane, which has a melting point of 72-75° C.

EXAMPLE XXIV

9-(*p*-2-ethylbutoxyphenyl)-9-methoxy-10-methyl acridaneBy proceeding according to Example XVII but starting with 9-(2-ethylbutoxyphenyl)-10-methyl acridane chloride (see Example XI), the compound 9-(2-ethylbutoxyphenyl)-10-methyl-9-acridol is prepared upon treatment with alkali. Upon refluxing this acridol with methanol, the compound 9-(p-2-ethylbutoxyphenyl)-9-methoxy-10-methyl acridane is prepared.

EXAMPLE XXV

2,9-methoxy-9-(p-n-hexaoxyphenyl)-10-methyl acridane

By following the process of Example XVII but starting with 2-methoxy-9-(p-n-hexaoxyphenyl)-10-methyl acridane chloride (see Example XIII), the compound 2-methoxy-9-(p-n-hexaoxyphenyl)-10-methyl-9-acridol is obtained upon treatment with alkali. Upon refluxing this acridol with methanol the compound 2,9-methoxy-9-(p-n-hexaoxyphenyl)-10-methyl acridane is formed.

EXAMPLE XXVI

1-chloro-9-methoxy-9-(p-n-hexaoxyphenyl)-4,10-dimethyl acridane

By following the process of Example XVII, but starting with 1-chloro-9-(p-n-hexaoxyphenyl)-4,10-dimethyl acridane chlorided (see Example XIV), the compound 1-chloro-9-(p-n-hexaoxyphenyl)-4,10-dimethyl-9-acridol is formed by the treatment with alkali. This acridol is in the form of nearly colorless crystals and has a melting point of 103.5-105.5° C. Upon refluxing this acridol with methanol, the compound 1-chloro-9-(p-n-hexaoxyphenyl)-4,10-dimethyl acridane is formed. This compound is a liquid at room temperature.

EXAMPLE XXVII

9-(p-n-decyloxyphenyl)-9-methoxy-10-methyl acridane

By following the procedure of Example XVII but starting with 9-(p-n-decyloxyphenyl)-10-methyl acridane chloride (see Example XIII), the compound 9-(p-n-decyloxyphenyl)-10-methyl-9-acridol is obtained. Upon refluxing this acridol with methanol the compound 9-(p-n-decyloxyphenyl)-9-methoxy-10-methyl acridane is formed.

The N-alkyl acridones may be prepared as indicated in Examples IA, IB and IC, for example, the N-methyl-2-methoxy-acridone may be prepared by reacting 2-methoxy acridine with dimethyl sulfate. 4,10-dimethyl-1-chloro-acridone may be prepared by reacting 1-chloro-4-methyl acridine with dimethyl sulphate.

As examples of other 9-acridol compounds and 9-methoxy derivatives which may be prepared are 9-(p-n-hexaoxyphenyl)-10-n-decyl-9-acridol, 9-(p-methoxyphenyl)-9-methoxy-10-n-decyl acridane, 9-(p-n-tetradecyloxyphenyl)-10-methyl-9-acridol and 9-(p-n-tetradecyloxyphenyl)-9-methoxy-10-methyl acridane.

Also, by replacing the methanol used for converting the acridols to the corresponding 9-alkoxy derivatives with other alcohols, ethers of other alkyl groups may be prepared. For example by refluxing 9-(p-n-hexaoxyphenyl)-10-methyl-9-acridol with ethanol, 9-(p-n-hexaoxyphenyl)-9-ethoxy-10-methyl acridane; with n-butanol, 9-(p-n-hexaoxyphenyl)-9-n-butoxy-10-methyl acridane.

To emphasize the totally unexpected antiseptic properties exhibited by representative compounds of this invention, the following table of comparative values is given:

		Bactericidal (5 Minutes)	Bacteriostatic
40	Acriflavin	1:1,000	1:33,000
	Rivanol (2-ethoxy-6,9-diamino acridane)		1:5,000

The term "bactericidal" refers to the maximum dilution which will kill a culture of *Staphylococcus aureus* in five minutes. "Bacteriostatic" refers to the maximum dilution which will prevent the growth of the abovementioned organism. Both tests are made by the official methods of the U. S. Food and Drug Administration.

Compounds according to the invention may be made up into a variety of pharmaceutical preparations for the application of these antiseptic compounds. Among the types of compositions of matter which have been prepared and used successfully are aqueous solutions, tinctures, dusting powders, tooth pastes, etc.

Due to the highly antiseptic properties and low toxicities of the compounds described, these preparations have many and varied applications in preventing and during bacterial infections.

As illustrative examples of the preparations referred to above are the following:

EXAMPLE XXVIII

75 The water soluble salts of the invention form

19

stable aqueous solutions and are effective as germicides even in very dilute solutions; while by practicing further dilution these solutions retain bacteriostatic action. As used in this specification the term "antiseptic" refers to a substance which prevents or arrests the growth of micro-organisms either by inhibiting their activity or destroying them. The word "germicide" refers to an agent which destroys microorganisms.

EXAMPLE XXIX

I have determined after a thorough investigation that aqueous solutions in 1:1,000 concentration are very desirable for practical use. Such a solution may be prepared by dissolving 1 unit by weight of the acridane antiseptic in 1,000 units of distilled water.

A suitable tincture using one of these halides may be prepared as follows:

EXAMPLE XXX

A composition with the following concentrations of its ingredients:

For 100 cc. volume—

0.1 gm. 9-(p-n-hexoxyphenyl)-10-methyl acridane chloride
54.0 cc. ethyl alcohol denatured
5.0 cc. acetone
41 cc. distilled water

Other acridane halides may be used in place of the acridane compound used here.

EXAMPLE XXXI

The antiseptic compounds disclosed herein may be made up for use in tooth pastes or powder form by embodying about 0.1% of the active ingredient in a conventional tooth paste or powder base.

EXAMPLE XXXII

A dusting powder may be prepared by incorporating about 1% of the antiseptic compounds of the invention into a therapeutically inert fine powder.

This application is continuation-in-part of my earlier application, Serial Number 781,758, filed October 23, 1947, now abandoned.

The present application is directed to applicant's novel antiseptic mineral-anion acridane compounds. Applicant's copending application Serial No. 191,088 of October 19, 1950, which is a division of the present application, is directed to applicant's novel 9-alkoxy-acridane compounds. These compounds are intermediates for and derivatives of the compounds of the present application. Applicant's novel acridol compounds are the subject matter of applicant's copending application Serial No. 250,185, filed October 6, 1951, which is a divisional application of the present application.

Others may readily adapt the invention for use under various conditions of service, by employing one or more of the novel features disclosed herein, or equivalents thereof. As at present advised with respect to the apparent scope of my invention, I desire to claim the following subject matter.

I claim:

1. An acridane compound characterized by the presence of an alkoxy-phenyl group at the 9-position and a hydrocarbon group at the 10-position, the alkyl group of said alkoxy group containing from one to fourteen carbon atoms and the hydrocarbon group at the 10-position containing from one to ten carbon atoms.

20

2. Substituted acridane compounds represented by the following formula:

wherein R is an alkyl group containing from one to fourteen carbon atoms inclusive; X is a monovalent radical selected from the class consisting of hydrogen, halogen, alkyl and alkoxy groups; Y is a hydrocarbon group containing from one to ten carbon atoms inclusive, and Z is a mineral acid anion.

3. The compound 9-(p-n-hexoxyphenyl)-10-methyl acridane chloride.

4. The compound 9-(p-n-butoxyphenyl)-10-methyl acridane chloride.

5. The compound 9-(p-hexoxyphenyl)-10-methyl acridane chloride.

6. The compound 9-(octoxyphenyl)-10-methyl acridane chloride.

7. The compound 9-(p-n-decyloxyphenyl)-10-methyl acridane chloride.

8. The process of preparing an acridane compound of claim 1, which comprises reacting an acridone compound with the lithium metal derivatives of alkoxybenzene.

9. The process of preparing a compound represented by the formula:

wherein R is an alkyl group containing from one to fourteen carbon atoms inclusive, X is a monovalent radical selected from the class consisting of hydrogen, halogen, alkyl and alkoxy groups; Y is a hydrocarbon group containing from one to ten carbon atoms inclusive, and Z is a mineral acid anion, which comprises: reacting the lithium metal derivative of an alkoxybenzene with a Y-N-substituted acridone; and then treating the resulting acridol with mineral acid.

10. The process of preparing a compound represented by the formula:

wherein R is an alkyl group containing from one to fourteen carbon atoms inclusive; X is a monovalent radical selected from the class consisting of hydrogen, halogen, alkyl and alkoxy groups; Y

is a hydrocarbon group containing from one to ten carbon atoms inclusive, and Z is a mineral acid anion, which comprises: reacting the 9-alkoxy derivative with a mineral acid.

11. The process of preparing a compound represented by the formula:

wherein R is an alkyl group containing from one to fourteen carbon atoms inclusive, X is a monovalent radical selected from the class consisting of hydrogen, halogen, alkyl and alkoxy groups; Y is a hydrocarbon group containing from one to ten carbon atoms inclusive, and Z is a halide, which comprises: reacting the 9-alkoxy derivative with gaseous hydrogen halide.

12. The process of preparing a compound represented by the formula:

wherein R is an alkyl group containing from one to fourteen carbon atoms inclusive, X is a monovalent radical selected from the class consisting of hydrogen, halogen, alkyl and alkoxy groups; Y is a hydrocarbon group containing from one to ten carbon atoms inclusive, which comprises: reacting the 9-alkoxy derivative with gaseous hydrogen chloride.

13. A composition of matter exercising action antagonistic to microorganisms and comprising as an active ingredient a 9-alkoxy-phenyl-10-hydrocarbon substituted acridane mineral acid anion salt; said ingredient being present in combination with a pharmaceutical carrier.

14. An antiseptic dusting powder comprising a therapeutically inert powder in combination with a compound according to claim 2.

15. An antiseptic composition of matter comprising a solution containing as an active ingredient a compound according to claim 2.

16. A composition according to claim 15 in the form of a tincture.

17. The process of preparing the compound represented by the formula:

wherein R is an alkyl group containing from one

to fourteen carbon atoms inclusive; X is a monovalent radical selected from the class consisting of hydrogen, halogen, alkyl, and alkoxy groups; Y is a hydrocarbon group containing from one to ten carbon atoms inclusive, and Z is a mineral acid anion, which comprises: reacting an acridol compound of the formula:

10

15

with a mineral acid.

18. The process of preparing a compound represented by the formula

25

wherein R is an alkyl group containing from one to fourteen carbon atoms inclusive, X is a monovalent radical selected from the class consisting of hydrogen, halogen, alkyl, and alkoxy groups; Y is a hydrocarbon group containing from one to ten carbon atoms inclusive, and Z is an ion selected from the class consisting of chlorine, bromine, and iodine, which comprises: reacting an acridol compound of the formula:

45

50

with a gaseous hydrogen halide.

19. The process of preparing a compound represented by the formula:

60

65

wherein R is an alkyl group containing from one to fourteen carbon atoms inclusive, X is a monovalent radical selected from the class consisting of hydrogen, halogen, alkyl, and alkoxy groups; Y is a hydrocarbon group containing from one to ten carbon atoms inclusive, which comprises;

75

23

reacting an acridol compound of the following formula:

with gaseous hydrogen chloride.

20. The process of preparing a compound represented by the formula:

wherein R is an alkyl group containing from one to fourteen carbon atoms inclusive, X is a monovalent radical selected from the class consisting of hydrogen, halogen, alkyl and alkoxy groups; Y is a hydrocarbon group containing from one to ten carbon atoms inclusive, and Z is a mineral acid anion, which comprises: reacting the lithium metal derivative of an alkoxy benzene with a Y-N-substituted acridone; warming the product within an alkanol and treating the resulting compound with a mineral acid.

21. The process of preparing a compound represented by the formula:

wherein R is an alkyl group containing from one to fourteen carbon atoms inclusive, X is a monovalent radical selected from the class consisting of hydrogen, halogen, alkyl and alkoxy groups; Y is a hydrocarbon group containing from one to ten carbon atoms inclusive, and Z is a mineral acid anion, which comprises: reacting the lithium metal derivative of an alkoxy benzene with a Y-N-substituted acridone; and converting the resulting acridol to the acridane salt shown in the formula.

22. A compound represented by the formula

24

in which Z is a mineral acid anion from the group consisting of mono and polyvalent anions.

23. A compound represented by the formula

in which Z is a mineral acid anion from the group consisting of mono and polyvalent anions.

24. A compound represented by the formula

in which R is an alkyl group containing from one to 14 carbon atoms inclusive.

25. A compound represented by the formula

in which R is an alkyl group containing from one to 14 carbon atoms inclusive.

26. A compound represented by the formula

in which R is an alkyl group containing from one to 14 carbon atoms inclusive.

27. A compound represented by the formula

25

in which Y is a hydrocarbon group containing from one to ten carbon atoms inclusive.

28. An antiseptic composition comprising an aqueous solution of a 9-alkoxy phenyl-10-hydrocarbon substituted acridane mineral acid salt.
